UNITED STATES PATENT OFFICE.

JOHN M. MARTIN, OF CLEVELAND, OHIO.

DESIGN FOR A MONUMENT.

Specification forming part of Design No. 5,971, dated July 2, 1872.

Specification describing a Design for a Monument, invented by JOHN M. MARTIN, of Cleveland, in the county of Cuyahoga, State of Ohio.

The nature of my design is fully represented in the accompanying photographic illustration, to which reference is made.

A represents a rectangular pedestal, on which the monument stands. B is the base of the frustum C, which consists of heavy moldings having parallel relation to the sides of the pedestal and frustum, which is also rectangular. Each corner of the frustum is truncated and replaced by a pilaster, D, provided each with a capital and base of plain molding. On the top of the frustum is a heavy projection of moldings, E, forming a kind of capital to the frustum, which also forms the base of the shaft F of the monu-

ment. Said shaft is an obelisk, on the top of which is a capital, adorned on the sides by pendants in *rilievo*. Also, near the foot of the shaft is a girdle of embossed pendants, similar in style to those near the crown or capital of the shaft, all of which constitute the design for the monument, and which is fully represented in the accompanying illustration, as above said.

Claim.

The herein-specified design for a monument, consisting of the several parts, substantially as described.

JOHN M. MARTIN.

Witnesses:

A. C. MARTIN,
ARCH. COCHRAN.
